[57] CLAIM

The ornamental design for a combined auxiliary seat storage device and audio unit for a jeep type vehicle, as shown and described.

DESCRIPTION

FIG. 1 is a perspective view of a combined auxiliary seat, storage device and audio unit for jeep type vehicle showing my new design; the broken line showing of a portion of a jeep type vehicle is for illustrative purposes only.

FIG. 2 is an enlarged top plan view thereof;
FIG. 3 is an enlarged front elevational view thereof;
FIG. 4 is a rear elevational view thereof; and
FIG. 5 is an enlarged side elevational view thereof the
opposite side being a mirror image of the side shown.FIG-1
